UNITED STATES PATENT OFFICE

ADOLF STEINBRÜCKNER, OF DUISBURG, GERMANY

MILL

Application filed November 30, 1927, Serial No. 236,749, and in Germany December 8, 1926.

The invention relates to a mill intended to grind minerals, earths, cereals and the like and having a grinding work which is limited circularly and may be a crushing or striking work.

The invention has reference to the manner of sifting the grits from the flour. According to the invention this sifting operation takes place at least for the greater part within the mill, and in particular by means of an air current which is led circularly around the circular chamber of the grinding work. In order to be able to adapt the quantity of supplied air to the need that varies according to the nature of the material to be ground, within the widest limits and exactly, that means in a manner causing a fine sifting, a branch is provided on the air conduit before its junction with the mill, through which branch a portion of the air current generated by a blower is prevented from entering the mill and is led to any other place of utilization or may be united again with the air current leaving the mill. To this end a device is provided serving for the regulation of the air current which eventually may be a long distance regulation for the current that is branched off before the mill.

In the circular chamber surrounding the grinding work a mechanical conveyer is further arranged for the material produced in the mill, which conveyer rotates in this chamber and co-operates with the above-mentioned pneumatic conveying or sifting device, this co-operation of the two conveyers within the mill taking place in such a manner, that the mechanical conveyer always supplies anew to the mill work the grits leaving the latter, whilst the pneumatic conveyer the air current of which does not enter the mill work but flows only around it and does thus not interfere with the grinding operation taking place therein, leads off the flour immediately. A further sifting may take place within a sifter attached to the mill, which sifter supplies again to the mill the material not yet ground finely enough. Under certain circumstances, however, the two mentioned conveying and sifting means arranged in com-

bination with the mill itself will do satisfying work.

In order to allow of my invention to be more easily understood, some preferred embodiments of a mill constructed according to my invention are illustrated by way of example in the drawings which accompany and form part of this specification. In these drawings: Figure 1 is a vertical section on the line C—D of Figure 2, Figure 2 is a vertical section on line A—B of Figure 1, Figure 3 is a fragmentary view of another embodiment, whilst Figure 4 is a vertical section through a third embodiment.

Referring now to these figures, *a* denotes the mill casing in which the mill work is arranged that is limited by a cylindrical body or ring *r*. The work shown in Figures 1 and 2 consists of three rollers *c* around which the ring *r* rotates, whilst in the embodiment shown in Figure 4 the work operates by strikers *b* which rotate whilst the ring *r* is stationary here. The material to be ground is applied to the mill work from a feeding means *g* of any design through a passage *h*.

Between the casing *a* and the ring *r* or *r*⁴, Figure 4, an annular space *e* is left, in which a mechanical conveyer rotates, consisting e. g. in a bucket conveyer *d*.

In the embodiment illustrated in Figures 1, 2 and 4 this conveyer *d* rotates independently of the mill work, whereby the advantage is afforded, of the rate of revolutions of the mill work and that of the conveyer being enabled to better be adapted to the special requirements thereof and independently of one another. In the embodiment illustrated in Figure 3 the conveyer, viz., the buckets *d*³, are arranged on the ring *r* itself at a certain distance away from its circumference. This construction offers the advantage of a special drive for the conveyer being dispensed with. On or nearly on the summit of the conveyer *d* channels *f* lead from the annular space *e* into the interior of the mill, so that the material that raises in the buckets *d* or *d*³ within the annular space *e* and emptied on the top thereof returns to the mill work through these channels *f*. Near its bottom the annular space *e* is equipped with a tangentially

arranged mouth piece m to which a blower n is attached. On the place where the mouth piece m opens into the annular space e the wall of the casing a has a horizontal guide 5 grate t . Before the mouth piece m a conduit o branches off in upward direction. In the embodiments shown in Figures 1, 2 and 4 this conduit o is united with a conduit j that opens on the top of the annular space e at 10 i , see Figure 1. A mixer k fitted with inner helically arranged baffle plates k^1 is arranged on the junction of the conduits o and j , the latter uniting at an acute angle. A damper p is arranged in the mouth piece m which 15 damper serves to more or less throttle the passage m^1 leading from the blower n to the annular space e . The damper p may be connected to an electric or mechanic long distance controlling apparatus denoted by p^1 . 20 The described mill operates in the following manner:

The material to be ground and fed from the feeding device g to the mill work falls, as far as it has been disintegrated correspondingly, on the bottom down into the annular space e through the gap a^1 left between ring r or r^1 and casing a , see Figure 2. In 25 the space e the grits are taken up by the conveyer d or d^1 and supplied anew to the mill work, whilst the flour is taken with in several layers by the air blown in in several jets through the guide grate t tangentially to ring r and is led off from the mill through the outlet i and conduit j . The power of the 30 air current can be so regulated, that the pneumatic conveyer takes off only the fine flour, whilst the mechanical conveyer supplies over and over again the grits, until even the latter have been so finely ground, that they are 35 also taken with by the air conveyer. In this manner a perfect sifting may be established within the mill itself, so that no sifting machine needs to be arranged behind the mill. Of course, a sifting device s can nevertheless 40 be inserted in the conduit j , by means of which device the coarse flour is again supplied to the mill at s^1 .

The regulation of the power and quantity 45 of the air is effected by adjusting the damper p , eventually from a distant station by means of the long distance controlling apparatus p^1 . The air that does not pass through the mill flows through conduit o and unites in the mixer k with the air leaving the mill through outlet i . In the mixer k the two air currents are completely mixed and, as the speed of the air current supplied through conduit o is superior to that of the air current supplied from outlet i , the first-named air-current exerts an injector-like action upon the last-named air current. Furthermore, as the air inlet m and the air outlet are located close to one another, the described conveying and 50 sifting air current travels the longest possible way within the mill and this merely

around the mill work and not even partly through the latter. The air current does not, further, interfere both with the return of the grits at the point f where the grits are supplied anew, and with the supply of the fresh material, as both material currents are led into the mill work through separate channels, whilst the conveying and sifting air current circulates outside around the mill work. Finally, due to the fact that the material is supplied to the work in two currents, viz, the fresh material and the return grit current, the load of the mill work becomes more uniform. 70

Instead of uniting the branched-off air current o again with the current flowing around the mill work, it may be led to another special place of utilization. 80

What I claim, is:—

1. A mill comprising a mill work having a cylindrical outer surface, a pneumatic conveyor arranged on the outer surface of said work and adapted to operate concentrically thereto and to lead off ground material from the mill, an air conduit leading to said conveyor, and an outlet in said air conduit before its junction with said conveyor to bypass a proportion of the air forced through the conduit to the conveyor. 85

2. A mill comprising a mill work having a cylindrical outer surface, a pneumatic conveyor arranged on the outer surface of said work and adapted to operate concentrically thereto and to lead off ground material from the mill, an air conduit leading to said conveyor, an outlet in said air conduit before its junction with said conveyor to bypass a proportion of the air forced through the conduit to the conveyor, and means for regulating the proportion of air bypassed through the outlet with respect to the proportion of air forced through the conduit to the conveyor. 90

3. A mill comprising a mill work having a cylindrical outer surface, a pneumatic conveyor arranged on the outer surface of said work and adapted to operate concentrically thereto and to lead off ground material from the mill, an air conduit leading to said conveyor, an outlet in said air conduit before its junction with said conveyor to bypass a proportion of the air forced through the conduit to the conveyor, and long distance controlled means for regulating the proportion of air bypassed through the outlet with respect to the proportion of air forced through the conduit to the conveyor. 100

4. A mill comprising a mill work having a cylindrical outer surface, a pneumatic conveyor arranged on the outer surface of said work and adapted to operate concentrically thereto and to lead off ground material from the mill, an air supplying conduit leading to and an air conduit leading away from, said conveyor, and an air bypassing conduit 105

- branched off from said air supplying conduit before the junction of the latter with said conveyer and opening into said air conduit leading away from said conveyer.
5. A mill comprising a mill work having a cylindrical outer surface, a pneumatic conveyer arranged on the outer surface of said work and adapted to operate concentrically thereto and to lead off ground material from the mill, an air supplying conduit leading to and an air conduit leading away from, said conveyer, a conduit branched off from said air supplying conduit before the junction of the latter with said conveyer and opening into said air conduit leading away from the latter, and an air mixer inserted on the junction of said branch and said last-named conduit. 70
6. A mill comprising a mill work having a cylindrical outer surface, a pneumatic conveyer arranged on the outer surface of said work and adapted to operate concentrically thereto and to lead off ground material from the mill, an air supplying conduit leading to and an air conduit leading away from, said conveyer, a conduit branched off from said air supplying conduit before the junction of the latter with said conveyer and opening into said air conduit leading away from the latter, and an air mixer inserted on the junction of said branch and said last-named conduit and having helical baffle plates. 80
7. A mill comprising a mill work having a cylindrical outer surface, a pneumatic conveyer arranged on the outer surface of said work and adapted to operate concentrically thereto and to lead off ground material from the mill, an air supplying conduit leading to and an air conduit leading away from, said conveyer, said two conduits opening close to one another into said conveyer opposite to the direction of the supplied air current, and a conduit branched off from said air supplying conduit before the junction of the latter with said conveyer and opening into said air conduit leading away from said conveyer. 90
8. A mill comprising a mill work having a cylindrical outer surface, a pneumatic conveyer arranged on the outer surface of said work and adapted to operate concentrically thereto and to lead off ground material from the mill, an air supplying conduit leading to and an air conduit leading away from, said conveyer, and a conduit branched off from said air supplying conduit before the junction of the latter with said conveyer and opening into said air conduit leading away from said conveyer at an acute angle. 100
9. A mill comprising a mill work having a cylindrical outer surface, a pneumatic conveyer arranged on the outer surface of said work and adapted to operate concentrically thereto and to lead off ground material from the mill, an air supplying conduit leading to and an air conduit leading away from, said conveyer, a conduit branched off from said air supplying conduit before the junction of the latter with said conveyer and opening into said air conduit leading away from the latter, and a sifting device inserted in the latter conduit. 110
10. A mill comprising a mill work having a cylindrical outer surface, a mechanical conveyer arranged on the circumference of said work and adapted to move concentrically thereto and to supply material to said mill work, a pneumatic conveyer arranged on the outer surface of said work and adapted to operate concentrically thereto and to lead off ground material from the mill, an air supplying conduit leading to and an air conduit leading away from, said conveyer, and a conduit branched off from said air supplying conduit before the junction of the latter with said conveyer and opening into said air conduit leading away from said conveyer. 120
11. A mill comprising a mill work having a cylindrical outer surface, a mechanical conveyer arranged on the circumference of said work and adapted to move concentrically thereto and to supply material to said mill work, a pneumatic conveyer arranged on the outer surface of said work and adapted to operate concentrically thereto and to lead off ground material from the mill, an air supplying conduit leading to and an air conduit leading away from, said conveyer, a conduit branched off from said air supplying conduit before the junction of the latter with said conveyer and opening into said air conduit leading away from the latter, and a sifting device inserted in the latter conduit. 130
12. In a mill, in combination, a material grinding medium, a mechanical conveyer for refeeding the material to the grinding medium and pneumatic means for conveying out of the mill the reground material which has previously been discharged from the grinding medium. 140
13. In a mill, in combination, a material grinding medium, a mechanical conveyer for refeeding the material to the grinding medium and pneumatic means for conveying out of the mill the reground material which has previously been discharged from the grinding medium, and means for preventing the air from the pneumatic means from passing into the grinding medium. 150
14. In a mill, in combination, a material grinding medium, and pneumatic means for conveying the ground material discharged from the grinding medium out of the mill, and means for causing the air from the pneumatic means to be circulated circumferentially around the exterior of the grinding medium. 160
15. In a mill, in combination, a material grinding medium, and pneumatic means for conveying the ground material discharged from the grinding medium out of the mill, 170

and means for causing the air from the pneumatic means to be circulated circumferentially around the exterior of the grinding medium, said air being prevented from passing into the grinding medium.

16. In a mill, in combination, a material grinding medium, a surrounding mechanical conveying means independent of the material grinding medium for conveying the material discharged from the grinding medium, and means for refeeding the material from the conveying means into the grinding medium.

17. In a mill, in combination, rotary grinding medium, rotary conveying means surrounding the grinding medium and independent thereof for conveying the material discharged from the grinding medium, independent drives for grinding medium and conveying means, and means for refeeding the material from the conveying means into the grinding medium.

18. In a mill, in combination, a rotary grinding medium including an open sided ring member, a cylindrical casing surrounding the ring member, the end walls of the casing spaced apart from the sides of the ring for permitting discharge of the ground material from the interior of the ring into the bottom of the casing.

19. In a mill, in combination, a rotary grinding medium including an open sided ring member, a cylindrical casing surrounding the ring member, the end walls of the casing spaced apart from the sides of the ring for permitting discharge of the ground material from the interior of the ring into the bottom of the casing, a rotary bucket conveyer surrounding the ring member for picking up the ground material discharged into the bottom portion of the casing, and means for refeeding the material into the interior of the ring from the rotary conveyer.

20. In a mill, in combination, a cylindrical casing, a grinding medium disposed centrally of the casing, and means for forcing air under pressure into the casing substantially tangentially to the peripheral wall thereof into a ring shaped unobstructed space between the peripheral wall and the outer surface of the grinding ring whereby it follows the curve of such space.

In testimony whereof I affix my signature.

ADOLF STEINBRÜCKNER.
